Patented Aug. 22, 1922.

UNITED STATES PATENT OFFICE.

ERNST SCHMALLER, OF RACINE, WISCONSIN, ASSIGNOR TO PAUL B. WOHLRAB, OF RACINE, WISCONSIN.

STEERING-POST TRANSMISSION MECHANISM.

1,426,914.

Specification of Letters Patent. Patented Aug. 22, 1922.

Application filed December 12, 1921. Serial No. 521,764.

To all whom it may concern:

Be it known that I, ERNST SCHMALLER, a citizen of the United States, and resident of Racine, in the county of Racine and State 5 of Wisconsin, have invented certain new and useful Improvements in Steering-Post Transmission Mechanism; and I do hereby declare that the following is a full, clear, and exact description thereof.

10 My invention pertains to new and useful improvements in steering post transmission mechanism for automobiles or other types of vehicles.

Heretofore it has been customary in certain types of transmission to employ a pair of oppositely sliding blocks operated by a rotatable steering post provided with right and left hand screw threads, which mesh with respective right and left hand threads 20 at adjacent ends of the blocks. A serious objection to this structure resides in the fact that a very small space of contact is permitted between the post and blocks, which results in excessive wear between the two.

25 In other structures a single block surrounds the steering post, but this is objectionable as it becomes necessary to take apart the entire transmission in order to unscrew and remove the block. Furthermore in this 30 type of transmission there is no means for taking up wear between the block and post.

It is therefore the object of the present invention to provide a structure which will overcome the disadvantages mentioned, and 35 it is more particularly the object to provide an arrangement wherein a maximum contact is obtained between the post and a single block at the same time permitting easy assembly or removal of the block when desired.

40 A further object resides in the provision of means for taking up wear between the block and steering post. It is also an object to substantially reduce the manufacturing 45 cost of devices of this character.

With the foregoing and other object and advantages in view the invention resides in the novel combination and arrangement of parts which will be hereafter more particularly described and claimed.

50 In the drawings:

Figure 1 is a vertical transverse section taken on the line 1-1 of Figure 2.

55 Figure 2 is a central vertical longitudinal section through the housing or casing in which the movable parts of the device are

disposed, said section being taken on the line 2-2 of Figure 1.

Figure 3 is a detail elevational view of the side closure for the housing or casing. 60

Referring more particularly to the several figures of the drawings, wherein similar reference characters indicate like parts, the numeral 1 denotes a steering post surrounded by the usual casing and having its lower 65 end enclosed in a substantially rectangular housing or casing 2. The housing 2 is provided with a side plate 3 forming a closure therefor, the same being removable so that access may be obtained to the interior of the 70 housing.

That portion of the steering post 1 which is disposed within the housing 2 is provided with screw threads 4, adapted to mesh with screw threads formed in the longitudinal 75 channel of the block 5, the latter being disposed within the casing and surrounding approximately one-half the circumference of the steering post 1.

As a result of this arrangement the rotation of the post 1 will cause the block to slide longitudinally. The casing 2 may be secured in any suitable manner to the frame of the vehicle on which it is mounted. The lower end of the steering post is rotatably mounted within the bearings 6 and 7 formed in the ends of the casing 2. The bearing 7 has an opening considerably larger than the bearing 6, to allow the end of the post with the screw threads 4 to be removed therethrough. The post 1 is provided with an enlarged bearing portion 8 and is adapted to cooperate with the bearing 7, while surrounding the post and secured thereto in any suitable manner adjacent the enlarged 95 portion 8, is a collar 9 which works against a pair of washers 10 for the purpose of taking the end thrust of the steering post. In order to prevent longitudinal movement of the post within the casing a nut 11 is threaded into the end of the bearing 7, which nut is provided with a recess adapted to receive and support the steering post casing 12.

100 The longitudinal movement of the block 5 is utilized to operate a rock shaft 13 journaled in the bearing 14 projecting from the side plate 3, the outer end of said shaft having mounted thereon a depending arm 15, which arm is connected to a steering link, 105 not shown. The inner end of the rock shaft 13 is provided with an arm 16 from which projects a stud 17 for disposition in a bear-

ing block 18, the latter being positioned in a vertical slot 19 formed centrally in the block 5. The bearing block 22 is substantially rectangular and the slot in which it is disposed is approximately the same width. It is obvious that when the steering post 1 is rotated, movement will be transmitted to the block 5, because of the screw thread connection, and in turn to the rock shaft 13, which will oscillate the arm 15 in the proper direction for steering the vehicle.

For the purpose of guiding the block 5 the cover 3 is provided with a lateral extension 20 having a depending tongue 21 adapted to project into the groove 22 formed longitudinally in the block 5. In order to permit the block 5 to be urged into connection with the steering post and to compensate for wear between these two members the cover 3 is made adjustable with relation to the casing 2 in which the steering post is journalled. This adjustment is obtained by means of the slots 23 in the cover and the bolts 24 for securing the same to the casing. The casing 3 is provided with a plurality of set screws 25 which engage the lateral extension 20 and lock the cover 3 in its adjusted position. From the foregoing it will be seen that as wear occurs between the block 5 and steering post the same may be compensated for by loosening the bolts 24 and turning down on the set screws 25 until the desired adjustment is obtained when the cover is locked or secured to the casing by tightening up the bolts 24.

It will further be noted that this construction permits easy assembling or dismantling of the mechanism inasmuch as the same is accomplished by loosening the set screws 25 and removing the bolts 24, which permits the cover 3 to be raised sufficiently until the tongue 21 clears the groove 22 at which point the cover together with the rock shaft is free to be removed. The block 5 which only partially surrounds the post 1 may then be removed without necessitating removal of the steering post.

I claim as my invention:—

1. A steering gear transmission mechanism comprising a steering post, a block 50 slidable on said post, a casing surrounding

said block and post, said casing being opened at one side, and a cover for said opening, said cover being adjustable with relation to the casing and serving as a guide for the 55 block whereby wear between the block and steering post may be taken up.

2. A steering gear transmission mechanism comprising a steering post, a block 60 slidable on said post, a casing surrounding said block and post, said casing being open at one side, and a cover for said opening, said cover being adjustable with relation to the casing and provided with a lateral extension 65 projecting into the casing and adapted to guide the block.

3. A steering gear transmission mechanism comprising a steering post, a block 70 slidable on said post and provided with a longitudinal groove, a casing surrounding said block and steering post, said casing being open at one side, and a cover for said opening, said cover being adjustable with relation to the casing and provided with a 75 tongue adapted to project into said groove to guide the block.

4. A steering gear transmission mechanism comprising a steering post, a block 80 slidable on said post, a casing surrounding said block and post, said casing being open at one side and a cover for said opening, said cover being provided with a guide for said block and having a slotted connection with the casing to permit its adjustment with relation thereto.

5. A steering gear transmission mechanism comprising a steering post, a block 90 slidable on said post and provided with a longitudinal groove, a casing surrounding 95 said post, said casing being open at one side, a cover for said opening, said cover being provided with a lateral extension having a depending tongue adapted to project in said groove to guide the block and means for adjusting the cover with relation to the casing.

In testimony that I claim the foregoing I have hereunto set my hand at Racine, in the county of Racine and State of Wisconsin.

ERNST SCHMALLER.
